UNITED STATES PATENT OFFICE.

OLIVER H. P. BASOM, OF CHITWOOD, MISSOURI.

GAS-BURNING FURNACE.

No. 880,000.

Specification of Letters Patent.

Patented Feb. 25, 1908.

Application filed September 11, 1906. Serial No. 334,196.

To all whom it may concern:

Be it known that I, OLIVER H. P. BASOM, a citizen of the United States, residing at Chitwood, in the county of Jasper and State 5 of Missouri, have invented a new and useful Gas-Burning Furnace, of which the following is a specification.

This invention relates to an apparatus for burning natural or consumers gas and combustible vapors generally for heating hot 10 water or steam boilers, furnaces, ovens, and equivalent devices.

The invention has for one of its objects to improve and simplify the construction and 15 operation of apparatus of this character, so as to be inexpensive to manufacture, to keep in repair and to operate, and so as to produce thorough combustion and high economy.

A further object of the invention is the 20 provision of a burner which is adapted to operate efficiently with gas at a comparatively low pressure and which is practically immune from explosions.

With these objects in view, and others, as 25 will appear as the nature of the invention is better understood, the invention comprises the various novel features of construction and arrangement of parts which will be more fully described hereinafter and set forth with 30 particularity in the claims appended hereto.

In the accompanying drawing, which illustrates one of the embodiments of the invention, Figure 1 is a longitudinal section of a fire box or boiler equipped with the gas 35 burning apparatus, the front portion of the boiler being shown in elevation. Fig. 2 is a front elevation of the boiler and fire box, the latter being partly in section.

Corresponding parts in the figures are indicated by similar characters of reference.

In the present instance I have elected to illustrate the gas burning apparatus applied to the fire box of a steam boiler, but I desire to have it understood that the same can be 45 used for hot water and steam boilers of various types, and for furnaces and other equivalent heating systems.

Referring to the drawing, 1 designates the boiler, 2 the setting therefor, 3 the fire box, 50 4 the combustion chamber, 5 the ash pit having door openings 6 and stationary grate bars 7. These various parts may be of any desired construction and arrangement.

Located within the fire box 3 and resting 55 on the grate bars are a plurality of mixing

devices disposed in parallel relation. These devices are preferably in the form of cylinders 8 of any size suitable for the fire box or furnace in which they are to be used. The cylinders are spaced apart from each other 60 and are surrounded by a mass of broken fire brick, or other refractory material, 9. The inner ends of the cylinders are each closed by a head 10. The front end of the cylinders 8 are approximately flush with the front wall 65 of the fire box and project through the same. The space around the front ends of the cylinders is walled in by the bricks 11, so that air is admitted to the fire box only through the cylinders and the ash pit. The top half of 70 each cylinder is provided with rows of perforations 12 which extend from the rear to a point slightly short of the front end. The unperforated portion 13 serves as an initial mixing chamber which is separated from the 75 main mixing chamber 14 by a perforated wall or disk 15, as shown in Fig. 1.

The front end of the initial mixing chamber 16 is open, so as to receive the jet of fuel from the burner nozzle, and to admit the necessary quantity of air to produce a combustible mixture. The air is drawn into the several cylinders by the combined action of the draft through the furnace and the injector action of the gas jets. The gas and air 85 are subjected to a preliminary mixing in the chamber 16 and then pass through the perforated wall 15 to the larger mixing chamber 14 where a more thorough mixing takes place. This enlarged mixing chamber also serves as 90 an expansion chamber wherein the pressure is practically removed entirely from the gas and air, the mixture being drawn evenly into the combustion chamber of the furnace by the draft created through the bed of fire-brick covering the grate. The fuel mixture from the large chamber is then drawn through the perforations 12 in the fire brick by the force of the draft through the furnace. While passing through the fire brick, the 100 mixture from the several cylinders is brought into contact with a larger quantity of air and intimately commingled therewith, so that the large proportion of air enables a large white flame to be produced that substantially fills 105 the fire box and combustion space of the furnace without producing soot and without the injurious effect of a blue flame. It will thus be seen that the gas supply in passing from the point of admission to the point of 110

2

combustion is subjected to three different stages of mixing with air, viz., in the initial chamber 16, in the intermediate chamber 14 and in the fire brick space around the several devices 8 and in passing through the perforated partitions separating them. It will be understood that an approximately unlimited supply of air is furnished to the fire brick space for the reason that the latter is in communication with the atmosphere through the grate and ash pit.

The gas supplying device comprises a plurality of nozzles 17 located at the front of the boiler with their tips slightly spaced apart from the open end of the initial mixing chamber 16, this being found to produce the best result. The nozzles 17 are connected to a manifold or header 18 at the floor line by pipes 19 each having a high pressure regulating hand valve 20 and a low pressure plug valve 21 adjacent the nozzle thereof. The header is connected with a suitable source of gas, the pressure of which is cut down to the desired point by the valves 20.

From the foregoing description, taken in connection with the accompanying drawing, the advantages of the construction and of the operation will be readily appreciated by those skilled in the art to which the invention appertains. To start the apparatus, the several valves 20 are opened and then the nozzle valves 21 opened one by one and a flame applied to the gas issuing from each nozzle. A small flame is thus produced in each initial mixing chamber 16 which, as the supply is increased by opening further the nozzle valves 21, becomes blue, and finally, as the gas supply is still further increased, the flame suddenly shoots through the cylinders and fire brick and burns in the firebox space above the fire brick. The operation of the apparatus is practically noiseless and back firing or explosion is prevented by means of the fire brick and shape of the mixing devices. With a furnace of a seventy horse power boiler equipped with this improved gas burning apparatus, it has been found that with a gas under a head of four ounces and a supply of eighty feet of gas per minute, the boiler will operate at full efficiency and the combustion takes place with a white flame that completely fills the fire box and furnace from front to back and passes through the boiler flues so as to heat the entire surface of the boiler exposed to the furnace.

I have described the principle of operation of the invention, together with the apparatus which I now consider to be the best embodiment thereof, but I desire to have it understood that the apparatus shown is merely illustrative and that various changes may be

made, when desired, as are within the scope of the invention.

What is claimed is:—

1. The combination with a furnace having a grate therein, of a hollow gas mixing cylinder extending longitudinally of the furnace above the grate thereof and having an open end projecting to the exterior of the furnace to receive air and having a perforated partition extending transversely of the cylinder at a point in proximity to the open end thereof dividing the cylinder into open and closed mixing chambers, the closed chamber being of greater capacity than the open chamber and serving as an expansion chamber for relieving the pressure from the gas, the upper wall of the closed chamber being provided with a set of emission orifices, a nozzle discharging into the open chamber of the cylinder at the exterior of the furnace, and serving to draw atmospheric air into the cylinder, and a bed of refractory material covering the grate and the perforated cylinder thereon, the draft of the furnace serving to draw the gas and air from the expansion chamber and creating a draft of air from beneath the grate to mix with the gas and air from the expansion chamber of the cylinder. 90

2. The combination with a furnace embodying a grate provided with a source of air supply beneath it, and a combustion chamber above it, of a row of horizontally arranged tubular bodies located above the grate, the inner end of each body being closed and the upper wall thereof being provided with gas emission orifices, the outer end of each body being open to the atmosphere, a gas discharge nozzle adjacent to and directed into the open end of each body, a manifold connected to and supporting the nozzles of the set, a perforated gas and air mixing partition arranged transversely of each body at a point adjacent to the open end thereof and dividing each body into an initial gas and air mixing chamber that is open to the atmosphere, and a relatively larger gas and air mixing and expansion chamber between the partition and the closed inner end of the tube, and a bed of refractory material covering the grate and the set of tubular bodies and serving to create a draft that will draw the mixed gas and air from the enlarged mixing and expansion chambers of the several bodies. 105

In testimony that I claim the foregoing as my own, I have hereto affixed my signature in the presence of two witnesses.

OLIVER H. P. BASOM.
